No. 893,233.

PATENTED JULY 14, 1908.

R. FOSTER.

POCKET FASTENER.

APPLICATION FILED OCT. 30, 1906.

Fig. 1.

A diagram of a segmented worm, likely a leech, showing its body segments and a central canal. The segments are numbered from 1 to 20. Segments 1 through 8 are on the left side, 9 through 17 are on the right side, and 18 through 20 are at the posterior end. A central canal is shown running through the segments, with a small opening indicated near segment 10.

UNITED STATES PATENT OFFICE.

RICHARD FOSTER, OF CAZENOVIA, NEW YORK.

POCKET-FASTENER.

No. 893,233.

Specification of Letters Patent.

Patented July 14, 1908.

Application filed October 30, 1906. Serial No. 341,352.

To all whom it may concern:

Be it known that I, RICHARD FOSTER, of Cazenovia, in the county of Madison, in the State of New York, have invented new and 5 useful Improvements in Pocket-Fasteners, of which the following, taken in connection with the accompanying drawings, is a full, clear, and exact description.

This invention relates to certain improvements in pocket fasteners adapted to be incorporated in the front and back of any pocket of any garment as parts thereof for the purpose of closing the mouth of the pocket and preventing accidental or malicious removal 10 of the contents. In other words, I have sought to provide any pocket with spring metal inserts or clasp sections which normally spring together to close the pocket, or may be positively locked together, as for instance, 15 when the wearer wishes to secure certain valuables against pick pockets.

A further object is to not only conceal the clasp sections between the fabric layers of the pocket, but also to make such clasp sections or inserts sufficiently thin to make 20 their detection from the exterior practically impossible.

Other objects and uses relating to the specific structure of the clasp sections will be 25 brought out in the following description.

In the drawings—Figure 1 is a perspective view, partly in section, and partly broken away, of a portion of the pocket and my improved clasp attached thereto. Fig. 2 is a 30 longitudinal sectional view taken on line 2—2, Fig. 1. Fig. 3 is a perspective view of the inner clasp section. Fig. 4 is a similar view of the outer clasp section.

This pocket fastener comprises essentially 35 inner and outer comparatively thin spring metal strips or plates —1—, and —2—, the inner strip being inserted in a fold —3— on the main body of the pocket near its upper edge, and is provided near its marginal edges 40 with apertures —4— for receiving stitches, as —5—, which secure the plate or strip —1— in operative position, making it practically a part of the garment. This strip —1— is therefore, concealed within the fold —3— and is provided with a substantially 45 central vertical slot —6— and a lengthwise slot —7—, the latter being located in one end

of the strip or plate —1—, the portions of the fold —3— registering with said slots being cut away for a purpose presently described. 55 The upper end of the slot —6— is enlarged for receiving the head, as —8—, of a stud —9— which is rigidly secured to a spring —10— on the strip or section —2—.

A spring bar —11— is mounted upon and 60 movable lengthwise of the inner face of the strip or plate —1— and is provided with a stud —12— projecting through the lengthwise slot —7— and having an enlarged head —13— of greater diameter than the transverse width of the slot to retain the spring-bar —11— in place upon the strip or plate —1—, the head —13— projecting into the pocket and serves as a finger-piece whereby the bar —11— may be moved endwise. This 65 sliding spring-bar —11— is located between the slot —6— and end of the strip —1— nearest the slot —7—, being extended beyond the latter slot and is rigidly secured to the stud —12—, which is somewhat smaller 70 in diameter than the width of the slot —7— to permit a limited lengthwise movement of the bar —11—.

A portion of the strip —1— is slit or cut and pressed inwardly forming a loop —14— 80 through which the adjacent end of the spring bar —11— nearest the slot —6— is guided, said loop serving as a further means for retaining the spring-bar —11— in its operative position. 85

The end of the bar —11— nearest the slot —6— is movable to and from a position across the enlarged upper end of said slot, and when moved to its inner position across said slot it serves to lock the stud —9— in 90 the lower contracted portion of the slot —6—, or rather prevents the stud —9— from being allowed to register its enlarged head with the enlarged upper end of the slot —6—, in which position it might be withdrawn from 95 locking engagement with the strip —1— when the bar —11— is shifted out of registration with the upper enlarged end of the slot —6—.

The spring strip or plate —2— is inserted 100 into a fold —15— on the upper edge of the outer side of the pocket in alinement with the plate —1— and is provided near its marginal edges with apertures —16— for receiving

stitches —17— by which the strip or plate —2— is permanently secured to the outer flap or side of the outer flap, or side of the pocket, as —a—. The strip —2— is therefore, concealed within the fold —15— and is provided with an aperture —18— through which the stud —9— projects, said stud being rigidly secured to the spring bar —10— and has its inner end movable into and out 10 of the slot —6—, and together with the strip —2— and fold —15— has a slight vertical movement to interlock the head —8— with the narrower lower portion of the slot —6—, the inner side of the fold —15— in registration 15 with the slot —18— being perforated to receive the stud —9—.

Both plates —1— and —2— are curved to conform to the contour of the body near where the pocket is located and are spring 20 tensioned toward each other so as to automatically close the mouth of the pocket, but in order to further lock the pocket in its closed position, I have provided the strip —2— with the stud —9— having an enlarged head —8— adapted to be passed through the enlarged upper end of the slot —6—, whereupon the stud is forced downwardly to bring the head —8— behind the reduced portion of said slot —6—, after which 25 the sliding bar —11— is operated by the finger through the medium of finger - piece —13— and stud —12— to force the inner end of the bar —11— across the enlarged upper end of the slot —6— thereby locking the stud 30 —9— in the slot against upward displacement or withdrawal, at the same time positively locking the upper edges of the pocket to each other to prevent accidental or malicious removal of the contents of the pocket.

40 The spring-bar —10— extends lengthwise in opposite directions from the stud —9— and has its opposite ends bearing upon the plate —2—, while its central portion to which the stud —9— is secured, is tensioned outwardly 45 so as to draw the head —9— firmly against the inner face of the bar —1— in the slot —6—, and also serves when detached from the plate or strip —1— to draw the head —8— against the inner face of the strip —2— 50 or fold —15—, thereby leaving a clear open space without obstructions or projections within the pocket and preventing any liability of injury to the fingers or catching onto articles which are being inserted into or being 55 removed from the pocket.

As shown in Fig. 2, one end of the spring-bar —10— is secured to the strip or plate —2— by a rivet —20—, the other end being free to slide longitudinally to allow for the 60 spring action of the central portion of the spring-bar 10.

In operation, assuming that the spring strips —1— and —2— are inserted in the manner described, into their respective folds

—3— and —15—, then when it is desired 65 to close the mouth of the pocket against removal of its contents, the spring strip or plate —2— is pressed inwardly, by hand, sufficiently to force the head —8— through the enlarged upper end of the slot —6—, 70 whereupon the stud —9— is depressed, also by hand, to force the head —8— into engagement with the contracted lower portion of the slot —6—, after which the sliding bar —11— is moved endwise, by hand, through 75 the medium of the head 13 until its end adjacent to the stud —9— extends partially across the upper enlarged end of the slot —6—, thereby locking the stud —9— against upward displacement and preventing 80 the separation of the plates —1— and —2— until after the bar —11— is returned to its inoperative position.

When it is desired to gain access to the pocket the wearer of the garment having a 85 pocket simply withdraws the lock bar —11— from across the upper end of the slot —6—, which permits the stud —9— to be elevated, bringing the head —8— into registration with the upper enlarged head of said slot 90 —6—, whereupon the plates —1— and —2— may be sprung apart, the spring —10— serving to automatically withdraw the stud outwardly through the slot —6— and into engagement with the inner face of the plate 95 —2— or the inner side of the fold —15— leaving the inner surfaces of the pocket practically smooth.

What I claim is:

1. In a pocket fastener, a spring plate secured to one side of the mouth of a pocket and provided with a vertical slot at a point intermediate its ends, said slot slightly tapering downwardly and having an enlarged upper end, another spring plate secured to the 105 opposite side of the pocket and provided with a circular aperture alining with the said slot, a spring arm secured at one end to said latter plate and provided with a stud movable through said aperture and slot, 110 said stud being provided with an enlarged head to prevent its removal from said aperture and adapted to retain said stud within the tapering portion of said slot and movable means for locking the stud in said slot. 115

2. In a pocket fastener, a spring plate secured to one side of the mouth of a pocket and provided with a transverse V-shaped slot at a point intermediate its ends, said slot having a rounded and enlarged upper 120 end, another spring plate secured to the opposite side of the pocket and provided with a circular aperture normally alining with the rounded end of said slot, a spring arm secured at one end to said latter plate and provided with a stud movable through said aperture and slot end, the latter named spring plate being capable of limited vertical move- 125

ment, for positioning the stud within the tapering portion of said slot, said stud being provided with an enlarged head to retain said stud within the tapering portion and said 5 first named plate having a longitudinally slideable spring bar for locking said stud within said slot.

In witness whereof I have hereunto set my hand this 26th day of October 1906.

RICHARD FOSTER.
